Primary Examiner — Jack Reickel*Assistant Examiner* — Keith J Wilson(74) *Attorney, Agent, or Firm* — Ohlandt, Greeley, Ruggiero & Perle, L.L.P.(57) **CLAIM**

We claim the ornamental design for the actuator orifice, as shown and described.

DESCRIPTION

FIG. 1 is a front view of an actuator showing our design; FIG. 2 is a front-top perspective view thereof; FIG. 3 is a front-bottom perspective view thereof; FIG. 4 is a front left perspective view thereof, wherein the front right perspective view thereof is a mirror image; and, FIG. 5 is a bottom view thereof. The broken lines in the drawings represent portions of the actuator button that form no part of the claimed design.
